UNITED STATES PATENT OFFICE.

EDGAR S. MITCHELL AND GEORGE A. CAMPBELL, OF HOMER, LOUISIANA.

EXTENSION CAR-STEP.

1,033,029.

Specification of Letters Patent. Patented July 16, 1912.

Application filed September 16, 1911. Serial No. 649,635.

To all whom it may concern:

Be it known that we, **EDGAR S. MITCHELL** and **GEORGE A. CAMPBELL**, citizens of the United States, residing at Homer, in the parish of Claiborne and State of Louisiana, have invented new and useful Improvements in Extension Car-Steps, of which the following is a specification.

In Patent Number 955,658, of April 19th, 1910 we show an extension car step supported in retracted and projected positions by a pair of arms connected to a pair of hangers which in turn are connected to a pair of brackets arranged in the angle between the riser and tread of a fixed car step. The several parts are so arranged as to permit of the hangers sliding on the brackets, whereby, to retract or project the step. This structure is quite efficient but relatively expensive, owing to the number of parts, therefore after experimenting with the structure above described we found that the result attained thereby could be produced with a structure having comparatively few parts and moreover we found that when certain parts in the new structure were contrasted with their equivalents in the old or those shown in the patent, these new parts were exceedingly simple in construction and owing to their arrangement, could be more readily operated all of which went to show that the new structure could be produced at a lower cost than that shown in the patent above referred to.

35 Therefore, the object of the present invention is to simplify, increase the efficiency and reduce the cost of extension car step structures shown in the Letters Patent above referred to.

40 Other objects will appear and be better understood from the following description taken in connection with the accompanying drawings, in which,

Figure 1 is a vertical section of car steps showing our invention applied thereto and in lowered or projected position. Fig. 2 is a view similar to Fig. 1 but showing the extension car step retracted or folded. Fig. 3 is a detail perspective of the several parts employed for supporting and operating the

extension step *per se*. Fig. 4 is a detail vertical section approximately on the line 4—4 of Fig. 1.

In the embodiment shown a single bracket *a* is substituted for the pair of brackets in our previous patent above noted and is arranged about midway of the ends of one of the stationary steps *b*. Instead of forming this bracket with an arm such as that shown with each of the brackets in our said patent and connecting the arm to the tread of the lowest stationary step, we further simplify this structure by securing the leaves *c*, *c* to the lowest step and for the link arms and cross bar which are supported by the bracket arms in our aforesaid patent, we substitute the swinging support or yoke *d* and connect the same to the leaves *c*. The said swing support or yoke *d* comprising a single piece of material of substantially U-shaped formation and comprising a horizontal supporting arm *d*' and vertical supporting arms *d*². Substitute the single supporting arm *e* and a pair of arms *f*, *f* which is secured to the opposite ends of the horizontal arm *d*' so as to coöperate with a plate *g* on the supporting arm said plate being disposed intermediately of the said arms *f*, *f* to form a three-point supporting step *h*. Thus we find, after eliminating one of the brackets shown in adjacent patent and substituting therefor a bracket less expensive to manufacture, that instead of weakening our structure, we have on the other hand, strengthened the same by increasing the supporting area for the step *h* and moreover we have rendered the device easier to operate, since it is now only necessary to disengage one latch and consequently compress one spring in order to project or retract the step, whereas in our above noted patent twice this amount of effort was necessary in order to operate the step.

The horizontal side 12 of the bracket α has the lateral ears or flanges 13 through 95 which pass the screws or bolts 14 for securing the bracket to the tread of one of the stationary steps. The vertical side 15 of the bracket α has the ears 16, 16 through 100 which pass the screws or bolts 17 which con-

nect the bracket to the riser of one of the stationary steps. The said ears 16, 16 also provide stops for the hanger 18 when the latter is vertical as shown in Fig. 1. The hanger 18 has a bushing 19 which turns in an opening in the vertical side 15 of the bracket and is held against displacement in any preferred manner, such as by a washer 20 arranged on a bolt 21 upon which is screwed the nut 22. This structure admits of the tightening of the nut 22 without danger of causing binding on the pivotal support for the hanger.

The latch comprises the pin 23 which passes through the oblong opening 24 in the hanger and connects the guide 25 with the arm 26 which latter operates to move the latch or pin 23 in the notches 27, 27 on the curved side 28 of the bracket *a* when the step is projected or retracted, the said arm being actuated by the spring 29 which is tensioned by a nut 30 screwed onto the rod 31 which is surrounded by the spring and connected to the arm 26 so as to slide in the guide 32 which forms a bearing for the spring 29. The pivot pin 33 which passes through the oblong opening 34 in the hanger 18, also connects the guide 25 with the arm 26 and in addition forms a support for the arm 8 which latter, as shown also has a portion 35 curving around the yoke 7.

The operation of our invention will be readily understood from the foregoing description and by reference to our previous patent. It will be seen, however, that when the parts are positioned as shown in Fig. 1, it is only necessary to pull upwardly on the outer portion of the extension step in order to depress the latch or pin 23 from engagement with the lower notch 27. This done, the step may be swung inwardly until the latch or pin engages with the upper notch 27. To project the step from the position shown in Fig. 2, it is only necessary to repeat the before mentioned operation of pressing upwardly on the step, until the latch is disengaged after which the step may be swung downwardly and outwardly to the position shown in Fig. 1.

Although we have shown and described one embodiment of our invention it is to be understood that we are not to be limited to the specific arrangement and construction of parts since various changes will be made, within the scope of the appended claims without departing from the spirit or sacrificing any of the advantages of the invention.

What we claim as new is:

1. In an extension car step, the combination with the fixed steps, of a bracket provided with means for connecting the same to the middle portion of the tread and riser

of one of the fixed steps, an angularly adjustable hanger provided with a bushing 65 for pivotally connecting the same to said bracket, a latch coöperating with the bracket to latch the hanger in various positions of adjustment, and a three-point support for the extension step including a 70 swinging yoke substantially of U-shaped structure including a horizontal arm supporting bar and oppositely disposed vertical extending arm supporting bars connected to one of the stationary steps and carrying 75 two arms connected to the swinging step, and a supporting arm connected to the swinging step and also connected to the latch for the purpose described.

2. In an extension car step, the combination with the fixed steps, of a bracket to lie in the angle between the tread and riser of a fixed step, an angularly adjustable hanger connected to said bracket, a latch for latching the hanger to the bracket in various positions of adjustment, a swinging support 85 of substantially U-shaped structure including a horizontal arm supporting bar and oppositely disposed vertical extending arm supporting bars, means carried by the said 90 oppositely disposed arm extending bars for connecting the swinging support to the stationary steps and means carried by the horizontal arm supporting bar for connecting the said yoke to an extension step and a supporting arm connected to the latch and adapted for operating the same.

3. In an extension car step, the combination with the fixed steps, of a bracket to lie in the angle between the tread and riser of a fixed step, an angularly adjustable hanger connected to said bracket, a latch for latching the hanger to the bracket in various positions of adjustment, a swinging support 100 of substantially U-shaped structure including a horizontal arm supporting bar and oppositely disposed vertical extending arm supporting bars, means carried by the said 105 oppositely disposed arm extending bars for connecting the swinging support to the stationary steps and means carried by the horizontal arm supporting bar for connecting the said yoke to an extension step and a supporting arm connected to the latch and adapted for operating the same and also 110 connected to the extension step at an intermediate point between the said means carried by the said horizontal arm supporting bar of the swinging yoke.

4. In an extension car step, the combination with the fixed steps, of a bracket to lie in an angle between the tread and riser of a fixed step, an angularly adjustable hanger connected to said bracket, a latch for latching the hanger to the bracket in various positions of adjustment, a swinging support 120

for the extension step connected to the stationary steps, and a supporting arm having a portion thereof curved around an intermediate portion of the swinging support and carrying means for connecting the same to the extension step, the said supporting arm being also connected to the latch and adapted for operating the same.

In testimony whereof we affix our signatures in presence of two witnesses.
